UNITED STATES PATENT OFFICE.

VICTOR V. DIBOVSKY, OF KINGSWAY, LONDON, ENGLAND.

BUFFERING DEVICE FOR MACHINE-GUNS.

1,298,912.

Specification of Letters Patent.

Patented Apr. 1, 1919.

Application filed April 10, 1918. Serial No. 227,776.

To all whom it may concern:

Be it known that I, VICTOR VLADIMIROVICH DIBOVSKY, a Russian subject, captain of the Russian naval general staff, and whose post-office address is Canada House, Kingsway, London, England, have invented certain new and useful Improvements in Buffering Devices for Machine-Guns, of which the following is a specification.

10 This invention relates to buffering devices for machine guns.

The rate of fire of an automatic gun can be increased by increasing the rate of reciprocation of the breech-block and other parts coöperating therewith. If the said rate of reciprocation is increased, disadvantages arise because the degree of shock imposed on the gun-mechanism is increased as well as its liability to jam. It is to a buffering device for use in the mechanism of a high-speed machine-gun, to counteract these disadvantages, that the present invention relates; the improvements thereunder are applicable to guns that are at present in use without necessitating alteration in the existing parts thereof, as well as to guns modified in design to incorporate the improvements.

15 The principal feature of the present invention is that in guns which comprise a crank-shaft there is provided at one or at each of the ends of that crank-shaft a spring and a fusee, the latter so disposed in relation to that spring that the leverage of the fusee shall increase as the crank moves toward that end of its path toward which it is impelled by the recoiling lock. Where the automatic gun already has a fusee-spring operating upon a fusee so that the 20 leverage exerted against the fusee by the spring diminishes as the crank moves back, it is only necessary to re-arrange the fusee in relation to the spring so that the contrary effect is produced.

25 Preferably if the gun is a Vickers gun the existing fusee-spring eccentric is thus altered at one end of the shaft and a similarly acting fusee and spring are applied to the opposite end of the same shaft, the two springs and their fusees thus coöperating to check the rapidity of the recoil and increase the rapidity of return.

The invention is hereinafter described in its application to a Vickers gun of a type 30 already well-known and firing small-arm ammunition.

In the accompanying drawings:—

Figure 1 is a side elevation, partly in section, and

Fig. 2 a plan of the rear end of a gun 60 with fusees and springs applied to the weapon in the manner hereinafter explained. In these figures the spring 1 is secured at its forward end by adjusting devices of any convenient type such as the screw A to 65 a lug L attached to the gun-casing; at its end remote from the lug it is connected by a chain C² to a fusee or eccentric E fixed to the crank-shaft CS in such relation to the main crank C of the gun, spring 1 and 70 chain C² that the leverage exerted against the fusee E by the spring 1 shall increase as the crank C approaches that end of the path toward which it is impelled by the recoil lock, that is to say, viewing Fig. 1, 75 as the crank-handle CH moves from the right in the figure toward the left.

At the left-hand side of the gun is a spring 1^a similar to the spring 1. The spring 1^a may be the original recoil-spring 80 of the Vickers gun, but according to the present invention it is connected to an eccentric E¹ or fusee, fixed to the left-hand end of the crank-shaft in such relation to the crank C and spring 1^a that the action 85 of the eccentric E¹, like that of the eccentric E, increases in opposition to the spring 1^a as the lock approaches the extreme of its recoil movement. Thus the springs 1, 1^a, and their eccentrics E, E¹, may be regarded 90 as two parts of a mechanism which operate in parallel and simultaneously co-act for the same purpose, namely that of satisfactorily checking the termination of a rapid recoil, and rapidly initiating the return movement. 95

It is to be understood that though the springs 1 and 1^a have been described as being in tension, springs in compression can be substituted in the manner well understood by engineers to give effects equivalent to those which are given by the aforesaid tension springs.

What I claim as my invention and desire to secure by Letters Patent is:—

1. In an automatic machine gun including a crank that is rocked at each firing operation, the combination with the crank, of a spring, and connections between the spring and crank adapted to act with gradually increasing leverage on the crank during recoil of the gun and oppositely during the return movement, whereby the initial return

of the crank and connected parts to firing position will be accelerated.

2. In an automatic machine gun including a crank that is rocked at each firing operation, the combination with the crank, of two springs arranged at opposite sides of the gun and both connected to the crank by means adapted to act with gradually increasing leverage on the crank during recoil of the gun and to accelerate the initial return movement of the crank toward firing position.

3. In an automatic machine gun including

a crank that is rocked at each firing operation, the combination with the crank, of a 15 fusee secured on one end of the crank, and a spring having its ends respectively connected to the fusee and gun, the connection between the spring and fusee being at the minimum distance from the axis of the 20 crank, whereby the spring will act with a constantly increasing leverage on the crank during recoil and will accelerate the initial return movement thereof.

In testimony whereof I affix my signature. 25

V. V. DIBOVSKY.
